C. KOHLER.

STEAM DRIVEN LOCOMOTIVE.
APPLICATION FILED JULY 14, 1921.

Patented Sept. 19, 1922.

Inventor
Conrad Kohler,
By *Henry J. Kohler* Atty.

UNITED STATES PATENT OFFICE.

CONRAD KOHLER, OF ZURICH, SWITZERLAND.

STEAM-DRIVEN LOCOMOTIVE.

Application filed July 14, 1921. Serial No. 484,650.

To all whom it may concern:

Be it known that I, CONRAD KOHLER, a citizen of the Republic of Switzerland, residing at Zurich, Switzerland, have invented 5 certain new and useful Improvements in Steam-Driven Locomotives; and I do hereby declare the following to be a clear, full, and exact description of the invention, such as will enable others skilled in the art to 10 which it appertains to make and use the same, reference being had to the accompanying drawings, and to letters or figures of reference marked thereon, which form a part of this specification.

15 The invention relates to improvements in steam driven locomotives and particularly to an arrangement for controlling the circuit of the water of condensation in steam driven locomotives provided with a surface 20 condensing plant, which arrangement comprises a pump for water of condensation which under normal working conditions delivers the total quantity of the water of condensation from the surface condenser into 25 the steam boiler.

With such locomotives many of the condenser pipes may be covered with water of condensation, whereby their efficiency is materially decreased, when the steam boiler is 30 filled with water to such an extent that a further feeding and consequently a further delivering of the water of condensation into the boiler is inadmissible. This is especially the case when the locomotive starts, at which 35 moment a great quantity of steam is consumed and the pump for water of condensation cannot return the large quantity of the water of condensation instantly into the steam boiler as the latter during the stopping of the train, has been supplied with 40 cold water from a tank for the purpose of preventing a useless generation of steam whilst the locomotive stops, so that the water level in the boiler is now already sufficiently 45 high.

The object of the present invention is to provide an arrangement of the afore-mentioned type which operates to prevent at all events an excessive filling or flooding of the 50 surface condenser of the locomotive with water of condensation. To this end the novel arrangement comprises a changing over device interposed in the water circuit between the condenser and boiler so that the 55 pump may deliver water from the condenser

either directly into the boiler or into a storage tank.

A constructional example of the device according to the invention is illustrated in the accompanying drawing, which represents a side view of a locomotive driven by a steam turbine and provided with a surface condensing plant. The steam is conducted from the steam dome 1 by means of a conduit 2 to a distribution-box 3 in which are

60 arranged valves adapted to shut off the steam supply and to be operated by the driver by means of hand wheels 4 and rods

5. From the distribution box 3 the steam flows through the conduits 6 to the steam 70 turbine 7 arranged in front of the boiler, which turbine actuates the driving wheels through the interposition of a double-transmission gearing, an intermediate shaft 8 and connecting rods, which latter are not

75 shown on the accompanying drawing. From the steam turbine 7 the exhaust steam flows through the conduit 9 into the surface condenser 10 and is condensed therein by the action of cooling water, which is

80 supplied to the condenser through the branch 11 and leaves it again through the branch 12 and is then conducted to a re-cooling device not shown on the drawing.

The water of condensation collecting in the 85 condenser is supplied to the condensate pump 14 through the conduit 13, which pump as well as the pump 15 for the cooling water is driven by an auxiliary steam

turbine 16 through the intermediary of a 90 transmission gearing. The water of condensation after its pressure has been raised by the pump 14 to the pressure of the steam boiler 19 is fed into the latter under normal

95 working conditions through conduit 17 and conduit 18. Inside the cab a hand lever

20 is provided serving to actuate, by the interposition of a rod 21, a three-way valve 22, interposed between the conduits

17 and 18, in such a manner, that the water 100 of condensation from the conduit 17 enters the boiler through the conduit 18 in the aforementioned manner and is evaporated therein. The generated steam is

lead off through pipe 2 and starts again 105 on the cycle. As soon as there is danger of the water level in the steam boiler rising too high, the driver operates the three-way valve 22 by means of the lever 20 and the rod 21 so that the connection between

110

the conduits 17 and 18 is interrupted and conduit 17 is connected to the conduit 23 which leads to a storage tank 24 situated below the cab. From this tank 24 fresh-
 5 water can be fed to the boiler 19 for instance by means of an injector 25 when the water level inside the steam boiler sinks too rapidly or when the steam is generated too rapidly owing to excessive heat. On
 10 account of the comparatively low pressure existing inside the tank 24 the condensate pump 14 which is preferably of the centrifugal pump type is able to draw off a much larger quantity of water of condensation
 15 from the surface condenser 10 than if the pump 14 has to discharge through the conduit 18 into the boiler 19 in a certain operative position of the three-way cock 22. In this manner it is at all events possible, also when the locomotive starts and therefore a large quantity of water of condensation is formed which cannot always be immediately returned to the boiler, to prevent an excessive flooding of the condenser
 20 25 10 with water of condensation.

I claim:

1. An arrangement for controlling the flow of the water of condensation of steam driven locomotives provided with a surface
 30 condensing plant, comprising a pump for water of condensation operatively connected to the surface condenser and to the steam boiler and adapted to deliver under normal working conditions the total quantity of the water of condensation from the surface condenser to the boiler, a changing

over device interposed in the connection from said pump to the boiler, a water storage tank, an operative connection between said device and said tank, and means to 40 operate said device so that said pump delivers the water of condensation at will either into the boiler or into said storage tank whereby an excessive accumulation of the water of condensation inside the condenser is avoided under all circumstances. 45

2. An arrangement for controlling the flow of water of condensation of steam driven locomotives provided with a surface condensing plant, comprising a pump for 50 water of condensation operatively connected to the surface condenser and to the steam boiler and adapted to deliver under normal working conditions the total quantity of the water of condensation from the surface condenser to the boiler, a three-way valve interposed in the connection from said pump to the boiler, a feed water storage tank, an operative connection between said valve and said tank, means to operate said valve 55 so that said pump delivers the water of condensation at will either into the boiler or into said storage tank whereby an excessive accumulation of the water of condensation inside the condenser is avoided under all circumstances, and means to deliver the water contained in said tank to the boiler. 60

In testimony that I claim the foregoing as my invention, I have signed my name.

CONRAD KOHLER.
